UNITED STATES PATENT OFFICE.

LAZRUBY C. HAMLINK, OF ST. LOUIS, MISSOURI, ASSIGNOR TO GAS BENCH CONSTRUCTION COMPANY, OF ST. LOUIS, MISSOURI, A CORPORATION OF MISSOURI.

RECUPERATIVE MUFFLE-FURNACE.

No. 852,506.

Specification of Letters Patent.

Patented May 7, 1907.

Application filed September 28, 1906. Serial No. 336,553.

To all whom it may concern:

Be it known that I, LAZRUBY C. HAMLINK, a citizen of the United States, and a resident of the city of St. Louis and State of Missouri, have invented certain new and useful Improvements in Recuperative Muffle-Furnaces, of which the following is a specification.

This invention relates to improvements in recuperative muffle furnaces designed for the destructive distillation of coal in the production of coal gas and its by-products.

The invention more particularly consists in the improved construction and arrangement of the recuperators or flues through which the secondary air is conducted into the furnace and which are located in the flue that forms the outlet for the waste or burned gases of the furnace.

Among the objects of the invention are to provide a large area of heating surface for said recuperators or secondary air flues, to provide this heating surface with as little frictional interference to the flow of the secondary air and of the waste gases as is possible, and to provide a construction in which the waste gas flues are readily accessible for cleaning, all of which will be fully understood from the following description of the construction illustrated in the accompanying drawings, in which—

Figure 1 is a half sectional elevation of a recuperative furnace or bench of eight retorts, the section being taken on line 1—1 of Fig. 2. Fig. 2 is a transverse sectional elevation of the furnace taken on line 2—2 of Fig. 1. Fig. 3 is a top plan section, the lower half being taken on line 3 of Fig. 1, and the upper half on line 3a of Fig. 1. Fig. 4 is a sectional elevation of the lower part of the furnace taken on line 4—4 of Fig. 1.

In said drawings, 1 designates the fire chamber or generator of the furnace and 2 the feeding hole through which the coke or coal for fuel is charged into the generator and onto its grate bars 3. The arched roof 4 of this fire chamber or generator is pierced by a plurality of openings or nostrils 5 leading up into the combustion chamber 6 within which the retorts 7 are mounted in such manner as to permit the products of combustion to circulate around them.

The primary air for the initial combustion is introduced into the ash pit 8 beneath the

grate bars through an inlet flue 9 (Fig. 3), the entrance of air to which is controlled by an adjustable door 10, and the products of combustion resulting from the passage of this primary air up through the fire chamber 1, pass into the combustion chamber 6 through the nostrils 5. The secondary air for completing the oxidation in the combustion chamber is introduced through inlet passages 11 and 12, the entrance of air to which is controlled by adjustable doors 13 and 14, the air from these passages being conducted upwardly through a number of hollow tile flues 15, that constitute the recuperators of the furnace, and being finally discharged into the lower middle portion of the combustion chamber through passages 16. The ultimate products of combustion leave the combustion chamber by passing downwardly through an outlet or smoke flue 17, and the hollow tile 15 are arranged across this flue 17 so that the secondary air passing through them is heated to a high temperature by the outgoing products of combustion in this smoke flue.

As thus far described, the construction of the furnace is generally old, and except as hereinafter set forth, may be varied widely without in any way departing from the present invention, which relates to the particular construction and arrangement of the hollow tile or recuperators 15 and the adjacent portions of the furnace. These recuperators, in the present improvement, extend across the flue 17 in an upwardly inclined direction, i. e., upwardly inclined toward the discharge end of the recuperator in each case, so that the secondary air in flowing through the recuperators from the inlet flues 11 and 12, in the bottom of the furnace, to the passages 16 through which it is discharged into the combustion chamber above, may constantly be rising in the manner natural to air which is being heated, while at the same time it is being directed across the smoke flues 17 a sufficient number of times to enable it to absorb the greatest practicable amount of the heat of the waste gases passing out through said smoke flue.

As herein shown, the recuperators 15 are provided in a number of horizontal rows, each recuperator of each row being arranged at the same inclination. There are four such rows in the construction illustrated, the two

lowermost rows consisting of five recuperators each, and the upper two rows consisting of six recuperators each. The recuperators may either be arranged in the same coincident vertical plane or staggered with relation to each other. In the construction shown, those of the lowermost row and the two uppermost rows are arranged in coincident vertical planes, while the recuperators of the third row are shown as staggered with relation to the planes of the other recuperators.

The air enters the lower end of the lowermost row of the recuperators through a horizontal passage 18, which communicates with and receives the air from the inlet passages 11 and 12. The air is discharged from these lowermost recuperators into a second horizontal passage 19, on the opposite side of the vertical smoke flue 17. The second row of recuperators 15 receives the air from this passage 19 and conducts it back across the smoke flue into a third horizontal passage 20, and the same action is then repeated by the third and fourth rows of recuperators which, in turn, conduct the air across the smoke flue from the passage 20 into an opposite passage 21, located above the passage 19, and then back across the smoke flue again into a passage 22 that is located above the chambers 18 and 20, and which communicates with the passages 16 through which the air is finally discharged into the combustion chamber.

The ends of the recuperators where they enter the several passages 18-22, are received between recessed tile 24, which form the top and bottom walls of these passages, and they are held laterally by tile 25 which are fitted between the ends of the adjacent recuperators and co-operate therewith to form the inner or smoke flue walls of said passages. In the case of the passages 19, 20 and 21, each of which receives the ends of two adjacent horizontal rows of recuperators, the contiguous ends of the latter are separated by horizontal rows of tile 26 which also separate the tile 24 and some of which are made hollow, as at 27, to permit the air to pass up through the passage on its way from one row of said recuperators to the next uppermost row. In the case of the lowermost and uppermost passages 18 and 22, each of which receives the ends of only a single row of recuperators, the separating tile 26 are, of course, not employed.

In the operation of the furnace thus described, the coke or coal fuel is charged into the generator 1 through the feeding hole 2 and onto the grate bars 3 to the depth of several feet. The furnace is then closed as nearly air tight as possible and just sufficient primary air is admitted through the inlet flue 9 to produce a primary combustion of this fuel. The carbon mon-oxid resulting from this primary combustion passes up

through the nostrils 5 and there comes in contact with the heated secondary air which enters from the recuperators through the passageways 16. The combustion is then completed in the combustion chamber by the reduction of the carbon mon-oxid to carbon dioxide which, after passing up and around the retorts 7, escapes downwardly through the smoke flue 17, where it incidentally envelops the recuperators 15 and gives up to them its surplus heat which is thereupon absorbed by the secondary air and carried back into the combustion chamber, as described. The provision of the two inlet passages 11 and 12 for the secondary air, enables the relative amounts of air admitted to the front and back of the bench to be separately regulated by means of the doors 13 and 14, the several horizontal passages 18-22 being to this end divided about midway of their length by tile 27 (Fig. 3), and the inlet passages 11 and 12 entering on opposite sides of these division tile, as shown. This, in effect, divides the recuperators into two vertical banks, each of which is separately supplied with air and one of which discharges toward the back of the bench, while the other discharges toward its front end.

The advantages in the peculiar construction and arrangement of the recuperators which characterize this invention, are the large area of heating surface provided for the secondary air flues or recuperators; and the reduction of friction in the conduction of the secondary air through the recuperators to the combustion chamber, together with the reduction in friction in the conduction of the products of combustion down through the smoke flue, as compared with that which obtains in furnaces of this character heretofore known. For it is obvious that the less the resistance offered to the ingoing secondary air and to the outgoing waste gases, the less chimney draft required, and the less chimney draft the more economical the fuel consumption and the longer the life of the settings, owing to the reduction in the cutting action of the flame in the combustion chamber and flues.

The improved recuperator construction described is applicable to any style or size of bench and the same hollow recuperator tile 15 and co-operating tile 24, 25 and 26 may be used, no matter how many tiers deep the bench is. And the construction is furthermore such as to enable the waste gas or smoke flue 17 to be readily cleaned at any time through cleaning doors 28 provided for the purpose (Figs. 1 and 4).

I claim as my invention:

1. In a recuperative furnace, a downwardly leading outlet flue for the waste gases, and a plurality of inclined recuperator flues extending in zigzag arrangement up the outlet flue and discharging into the combustion chamber.

ber, said recuperative flues being composed of a succession of rows of separate hollow tile, the upper ends of each row of which are arranged to discharge into the lower ends of the next superjacent row, and means for admitting secondary air into the lower row of tile, to be heated by the waste gases of the surrounding outlet flue and discharged into the combustion chamber, substantially as and for the purpose set forth.

2. In a recuperative furnace, a downwardly leading outlet flue for the waste gases, horizontal passages formed on opposite sides of said outlet flue, and upwardly inclined hollow tile recuperators extending across said flue and communicating with said passages at their opposite ends to form a continuous flue through which secondary air is discharged into the combustion chamber of the furnace, substantially as and for the purpose set forth.

3. In a recuperative furnace, a downwardly leading outlet flue for the waste gases, horizontal passages formed on opposite sides of said outlet flue, upwardly inclined hollow tile recuperators extending across said flue and communicating with said passages at their opposite ends to form a continuous flue for

the secondary air, a partition dividing said passages so as to separate the recuperators into two banks, air inlets leading into the lowermost passage from opposite banks of recuperators to the front and back of the bench, substantially as and for the purpose set forth.

4. In a recuperative furnace, a downwardly leading outlet flue for the waste gases, horizontal passages formed on opposite sides of said outlet flue, upwardly inclined hollow tile recuperators extending across said flue and communicating with said passages at their opposite ends to form a continuous flue through which secondary air is discharged into the combustion chamber, and co-operating tile forming the inner walls of said passages and receiving the entering ends of the recuperators, substantially as and for the purpose set forth.

In testimony, that I claim the foregoing as my invention, I affix my signature in presence of two subscribing witnesses, this 14th day of September, A. D. 1906.

Correction in Letters Patent No. 852,506.

It is hereby certified that in Letters Patent No. 852,506, granted May 7, 1907, for an improvement in "Recuperative Muffle-Furnaces," in the grant, and in the heading, preamble, and signature to the specification, the name of the patentee is erroneously written and printed "Lazruby C. Hamlink," whereas said name should be written and printed *Lazenby C. Hamlink*; and that the said Letters Patent should be read with this correction therein that the same may conform to the record of the case in the Patent Office.

Signed and sealed this 31st day of October, A. D., 1911.

[SEAL.]

E. B. MOORE,
Commissioner of Patents.

ber, said recuperative flues being composed of a succession of rows of separate hollow tile, the upper ends of each row of which are arranged to discharge into the lower ends of the next superjacent row, and means for admitting secondary air into the lower row of tile, to be heated by the waste gases of the surrounding outlet flue and discharged into the combustion chamber, substantially as and for the purpose set forth.

2. In a recuperative furnace, a downwardly leading outlet flue for the waste gases, horizontal passages formed on opposite sides of said outlet flue, and upwardly inclined hollow tile recuperators extending across said flue and communicating with said passages at their opposite ends to form a continuous flue through which secondary air is discharged into the combustion chamber of the furnace, substantially as and for the purpose set forth.

3. In a recuperative furnace, a downwardly leading outlet flue for the waste gases, horizontal passages formed on opposite sides of said outlet flue, upwardly inclined hollow tile recuperators extending across said flue and communicating with said passages at their opposite ends to form a continuous flue for

the secondary air, a partition dividing said passages so as to separate the recuperators into two banks, air inlets leading into the lowermost passage from opposite banks of recuperators to the front and back of the bench, substantially as and for the purpose set forth.

4. In a recuperative furnace, a downwardly leading outlet flue for the waste gases, horizontal passages formed on opposite sides of said outlet flue, upwardly inclined hollow tile recuperators extending across said flue and communicating with said passages at their opposite ends to form a continuous flue through which secondary air is discharged into the combustion chamber, and co-operating tile forming the inner walls of said passages and receiving the entering ends of the recuperators, substantially as and for the purpose set forth.

In testimony, that I claim the foregoing as my invention, I affix my signature in presence of two subscribing witnesses, this 14th day of September, A. D. 1906.
